CLAIM

The ornamental design for an end casing for a fishing reel, as shown and described.

DESCRIPTION

FIG. 1 is a front and left side perspective view of an end casing for a fishing reel showing our new design, the dotted line portion depicting a reel structure for illustrative purpose only and does not form a part of the claimed invention;

FIG. 2 is a rear and left side perspective view of the end casing shown in FIG. 1;

FIG. 3 is a front elevational view of the end casing shown in FIG. 1;

FIG. 4 is a rear elevational view of the end casing shown in FIG. 1;

FIG. 5 is a left side elevational view of the end casing shown in FIG. 1;

FIG. 6 is a right side elevational view of the end casing shown in FIG. 1;

FIG. 7 is a top plan view of the end casing shown in FIG. 1; and

FIG. 8 is a bottom plan view of the end casing shown in FIG. 1.
